UNITED STATES PATENT OFFICE

148,537

DESIGN FOR A BEVERAGE STIRRER

Todd Harris, Brooklyn, N. Y.

Application December 27, 1945, Serial No. 125,054

Term of patent 14 years

(Cl. D44—29)

To all whom it may concern:

Be it known that I, Todd Harris, a citizen of the United States, residing at Brooklyn, in the county of Kings and State of New York, have invented a new, original, and ornamental design for a Beverage Stirrer, of which the following is a specification, reference being made to the accompanying drawing, forming a part thereof.

I claim:

The ornamental design for a beverage stirrer, substantially as shown.

TODD HARRIS.
